CLAIM

The ornamental design for a television, as shown and described.

DESCRIPTION

1. Television

1.1 : Front perspective view

1.2 : Rear perspective view

1.3 : Front view

1.4 : Rear view

1.5 : Left view

1.6 : Right view

1.7 : Top view

1.8 : Bottom view

1.9 : Partial enlarged front perspective view, taken from square 1.9 in reproduction 1.1

1.10 : Partial enlarged front perspective view, taken from square 1.10 in reproduction 1.1

1.11 : Partial enlarged left view, taken from square 1.11 in reproduction 1.5

Reproduction 1.9 and 1.10 are enlarged views of portion of reproduction 1.1 respectively represented by the square in dash dot lines and curvy lines and the numbers; reproduction 1.11 is a enlarged view of portion of reproduction 1.5 represented by the square in dash dot lines and curvy lines and the number. The dash-dash broken lines indicate portions of the television that form no part of the claimed design. The dot-dash broken line boxes and connected wavy lines in reproductions 1.1, 1.5, 1.9, 1.10, and 1.11 are included for the purpose of illustrating the partial enlarged view and form no part of the claimed design.

1 Claim, 11 Drawing Sheets
